William C. Donville
his ATTORNEY.

UNITED STATES PATENT OFFICE.

ROBERT B. FOSTER, OF WELLSVILLE, OHIO.

FLANGE WRENCH.

1,425,845.

Specification of Letters Patent. Patented Aug. 15, 1922.

Application filed February 23, 1922. Serial No. 533,607.

To all whom it may concern:

Be it known that I, ROBERT B. FOSTER, a citizen of the United States, residing at Wellsville, in the county of Columbiana 5 and State of Ohio, have invented certain new and useful Improvements in Flange Wrenches; and I do hereby declare the following to be a full, clear, and exact description of the invention, such as will enable 10 others skilled in the art to which it appertains to make and use the same.

This invention relates to flange wrenches, and more particularly to a flange wrench adapted for use in screwing flanges on steam 15 and ammonia pipes.

The main object of the invention is to provide a simple, efficient and inexpensive device of the character referred to, that may be easily and quickly adjusted to adapt it 20 to be applied to either a small flange or a large flange, or to fit flanges of different kinds and sizes, either round, square, oval, or a three-cornered flange, the device being especially designed and adapted for screwing 25 flanges of different sizes on steam and other pipes, such as are used, for example, in ice making machines, requiring steam-tight fittings. A further object of the invention is to provide a device for the purpose 30 stated that can be easily and quickly adjusted and used by a single workman, thus economizing in both time and labor, instead of requiring two workmen, as is necessary in using flange wrenches as heretofore 35 ordinarily constructed, with drift pins and pull-bars or levers which require one man to work the drift pins and another to work the lever, in order to operate the device with any speed.

40 The invention will first be hereinafter more particularly described, with reference to the accompanying drawings, which are to be taken as a part of this specification, and then pointed out in the claims at the 45 end of the description.

In said drawings,

Fig. 1 is a perspective view of a flange wrench embodying my invention;

Fig. 2 is a side elevation of the same, illustrating its application to the front face or side of a steam pipe flange; and

Fig. 3 is a side elevation, illustrating its application to the back or rear face of an ammonia pipe flange.

55 Referring to said drawings, in which the same reference characters are used to denote

corresponding parts in different views, the letter A denotes a rigid preferably iron bar of about eighteen inches in length, having pivoted thereto, about twelve inches from 60 one end, a swinging arm B, carrying a pin or pins b at its free end, for engagement with a hole in a pipe flange, while the bar A carries a similar pin or pins at the end thereof nearest the free end of said arm, for 65 engagement with a hole on the opposite side of said flange, thus forming a lever of the second order for turning the flange; the swinging arm being considered as the weight 70 and the pin on the shorter arm or shank 75 portion of the lever as its fulcrum, and the longer arm thereof forming a handle. The swinging arm is curved upon the arc of a circle, or crescent-shaped in form, and is preferably bifurcated at one end, so as to straddle the bar A, to which it is secured by a pivot pin or rivet b¹, and it has secured to its free end or formed integrally therewith studs or pins b, which project in opposite 80 directions from opposite sides thereof. The short arm or shank a of said bar or lever A is also formed or provided with studs or pins a¹ at or near the free end thereof, which project in opposite directions from opposite sides thereof, as shown, thus adapting the 85 device to be applied to a flange on either side, or in reversed position. But it may be desirable in some cases to have a single pin projecting from one side only. The pins of both the lever and swinging arm are 90 formed preferably of a high grade steel and driven through holes in the end of the lever and arm so as to insure a tight fit, while the lever and swinging arm are preferably constructed of malleable iron. But other material and other securing means for the pins 95 may be used.

In operation, the lever and swinging arm are adjusted to adapt a pin on one to engage a hole in the flange C, for example, of a 100 steam-pipe, while a pin on the other engages a hole on the opposite side of the flange, and by manipulating the lever the flange is turned part-way around, proportionate to the throw of the lever, whereupon the pins 105 are withdrawn and engaged with another set of holes, and the lever again operated, and so on until the flange is firmly screwed on or into the desired position.

It will be observed that my improved 110 wrench is operated by a single workman and with a quick adjustment of the swing-

ing arm from one set of holes to another, and to suit flanges of different sizes, either large or small, and varying in size from one to twelve inches, using the same wrench, 5 thus effecting a saving of both time and labor incident to using flange wrenches of the kind heretofore ordinarily employed, which require two men to operate them, in order to make any speed—one man to manipulate 10 the drift pins and another man to manipulate the pull-bar or lever. This wrench is also equally well adapted to be applied to either side or face of a flange, being operable from either side of the pipe on 15 which the flange is to be screwed. Its application to the front face of a steam pipe flange is shown in Fig. 2 of the drawings, and as the front faces of ammonia pipe flanges are uneven, its application to the 20 back or rear face of an ammonia pipe flange is shown in Fig. 3.

The wrench may be made of any desired size to suit flanges of different kinds and sizes, the same wrench being adapted to be 25 used on flanges of different sizes, varying for example from a twelve inch flange to a one inch flange, and also adapted to fit different kinds of flanges, either round, square, oval, or a three-cornered flange, without requiring any adjustment other than to vary 30 the space between the free end of the short arm or shank of the lever and the free end of the crescent-shaped arm, by either bringing them closer together or moving them 35 further apart, according to the size of the flange to be screwed on and the distance between holes with which the pins on the lever and swinging arm are to engage. For a

twelve inch flange, for example, the length of the hand lever should be about eighteen 40 inches, and the length of the swinging arm about six inches, allowing a twelve inch swing.

Having thus described my invention, what I claim as new and desire to secure by Letters-Patent of the United States is;

1. A flange wrench comprising a rigid bar having a swinging arm of crescent-shaped form pivoted thereto near one end so as to provide at one side of said pivotal connection a handle forming the long arm of a lever and at the other side a straight short arm, said short arm and said swinging arm each provided at its free end with laterally projecting pins, and said swinging 55 arm having its concave surface facing said straight short arm.

2. A flange wrench comprising a rigid metal bar having secured thereto near one end a swinging arm of crescent-shaped form, 60 the other end of said bar forming a handle or the long arm of a lever; said swinging arm being provided at its free end with a laterally projecting pin or pins and a laterally projecting pin or pins on the free 65 end of the short arm of the lever; said short arm being straight and the concave surface of said swinging arm facing said short arm, substantially as described.

In testimony whereof I affix my signature 70 in the presence of two witnesses.

ROBERT B. FOSTER.
